CLAIM

The ornamental design for a produce holder, as shown and described.

DESCRIPTION

FIG. 1 is a front elevational view of a produce holder for holding fruits and vegetables illustrating my new design therefore and with a hammock and hanger structure for holding the produce shown as environment in phantom line and do not form any part of the claimed design;

FIG. 2 is a top plan view thereof;

FIG. 3 is a bottom plan view thereof; and,

FIG. 4 is a side elevational view thereof, the opposite side being a identical mirror image thereof.
